UNITED STATES PATENT OFFICE.

LULU M. SCOTT, OF BAXTER SPRINGS, KANSAS.

AUTOMOBILE-LOCK.

1,315,868.

Specification of Letters Patent. Patented Sept. 9, 1919.

Application filed March 28, 1919. Serial No. 285,753.

To all whom it may concern:

Be it known that I, LULU M. SCOTT, a citizen of the United States, residing at Baxter Springs, in the county of Cherokee and State of Kansas, have invented new and useful Improvements in Automobile-Locks, of which the following is a specification.

This invention relates to means for locking automobiles against use by unauthorized persons during the owner's absence.

The principal object of the invention is to provide means for locking the brake lever in braking position and at the same time to shut off the gasoline supply and to break the electric circuit.

Another object of the invention is to actuate the foregoing means by the forward movement of a member which is adapted to be moved by the foot or hand and to provide a spring lock for holding the said member in its forward position.

Still another object of the invention is to provide a small case for containing all the parts of the device with means for securing the same to the frame of the automobile.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a plan view showing the device in place on an automobile;

Fig. 2 is a side view of the device itself;

Fig. 3 is an end view thereof;

Fig. 4 is a horizontal section;

Fig. 5 is a like view with the parts in a different position;

Fig. 6 is a bottom view; and

Fig. 7 is a section on line 7—7 of Fig. 4.

As shown in these views, I provide a casing 1 which has a downwardly extending part 2 which is provided with the right angular extensions 3 containing the holes 4 for receiving the bolts for securing the casing to the frame of the automobile. As shown in Fig. 1, the casing is so situated as to be adjacent the brake lever 5 of the automobile. The end walls of the casing are each provided with an opening 6, said openings being located adjacent one side of the casing. A locking member 7 is located

in said casing with its ends engaging said openings. The said member is of greater length than the casing so that its ends will project therefrom though when in retracted position its forward or locking end will be flush with the forward end of the casing. This member is provided with a slot 8 and the casing is provided with a pin 9 which projects upwardly from the bottom of the casing into said slot. A spring 10 has one end secured to the member by a pin 11 and this other end engages said pin 9. This spring normally holds the lock member in its retracted position. The locking member is provided with a projection 12 on one side thereof which engages one of the walls of the casing to limit the rearward movement of said member. A handle 13 is secured to the rear end of said locking member and projects upwardly therefrom.

The means for locking said member in projected position consist of a bolt 14 sliding in guideways 15 formed in the casing by the recessed lugs 16. This bolt is located at right angles to the member and is provided with an inclined end which is adapted to engage with either one of a pair of recesses 17 formed in the adjacent side of the locking member 7. As shown, each of these recesses is provided with a straight wall and an inclined wall so as to permit the locking member to move forwardly without being held by the locking bolt, but said member will be held against rearward movement by the straight edge of said locking bolt engaging the straight wall of the recess. The locking bolt is normally held in engagement with one of said recesses by means of a flat spring 18 having one end engaging the studs 19 in the casing and its other end engaging a slot in said locking bolt. The casing includes a top 20 which is provided with an upwardly extending circular portion 21 and this portion receives the lock barrel 22 having the keyhole 23 therein. This barrel has pivoted thereto a link 24 which has its lower end engaging the bore of a tubular stud 25 formed on the bottom of the casing. This link passes through a slot 26 formed at one end of a link 27, the other end of which is pivoted to the locking bolt by a pin 28. It will thus be seen that when a key is inserted in the lock barrel and the same turned the vertical link will be turned so that the horizontal link 27 will be rocked to move the locking bolt against the action of its spring and out of the recess

in the locking member. As soon as the key is released the spring will return the locking bolt to normal position. It will thus be seen that it is simply necessary to move 5 the locking member either by the hand or foot engaging the handle 13, into projected position to lock the the brake lever against movement. The forward movement of the locking member will force the locking bolt 10 rearwardly out of engagement with the first recess 17 and then when the second recess comes opposite said locking bolt the same will spring forwardly into the recess with its straight side engaging the straight wall 15 of the recess and thus prevent the return movement of the locking member until a key is used to withdraw said locking bolt. When the key is inserted and the lock withdrawn, the locking member will return to its re- 20 tracted position by the spring 10. As be- fore stated, the casing is so situated that the braking lever will pass along the end thereof so that when it is in braking position and the locking member is projected the 25 end of said member will prevent the return of said lever.

I also provide means for braking the electric circuit when the locking member is in locking position and to do this I form a 30 recess in one side of the locking member and place therein a block 29 of insulating material. A spring contact 30 is located in the casing with one end in sliding engagement with said locking member. This contact is 35 provided with a binding post 31 which passes through the bottom of the casing and both the contact and post are insulated from the casing. One of the wires of the circuit is to be connected to said post. When the 40 locking member is in unlocking position the contact will engage the metal part of said member so that the circuit is completed through the metal parts of said casing and the automobile. When the locking member 45 is in locking position a spring contact will engage the insulated block and thus the circuit will be broken so that no spark is made at the spark plugs.

I also provide means for shutting off the 50 gasoline supply when the locking member is in locking position. To do this I locate a valve chamber 32 on one side of the extension 2 underneath the casing. This chamber is provided with the inlet and outlet 55 ports for receiving the ends of the gasoline supply pipes so that the gasoline must flow through said chamber to reach the engine. A valve 33 is located in said chamber to control the passage therefrom and the valve 60 stem passes through the upper part of the chamber and is provided with an arm 34. 35 indicates a lever pivoted intermediate its ends to the lower part of the casing and hav-

ing one end connected with said arm and its other end provided with the slot which receives a pin 36 carried by an arm 37 which is connected with an end of the locking member. The lever is also provided with a slot which engages the pivot pin. It will thus be seen that when the locking member 70 is in retracted position the valve will be opened to permit the gasoline to pass to the engine, but when said member is in locking position the connections between the valve and member will close said valve. 75

When the driver is to leave his car and wishes to lock the same, it is simply necessary to place his foot against the handle and push the locking member into locking position. This will hold the braking means 80 in braking position, the electric circuit will be broken and the gasoline shut off from the engine. When the driver returns it is simply necessary for him to insert the key in the keyhole and turn the lock when the locking member will spring back into un- 85 locking position and this will complete the electric circuit and turn the valve to permit the gasoline to flow to the engine.

The device is designed to be placed under 90 the floor of the automobile. When this is done it will be necessary to cut an opening to receive the upper end of the circular enlargement and to make a slot to permit the handle to pass through. 95

What I claim is:—

1. A locking device for automobiles, comprising a casing, a sliding member therein arranged to engage the brake lever when in its projected position, a spring bolt for holding the member in projected position, means on the bolt for making and breaking the electric circuit and means actuated by said member for interrupting the gasoline supply to the engine. 100

2. A locking device for automobiles, comprising a casing, a sliding member therein arranged to engage the brake lever when in its projected position, a spring for holding the member in its retracted position, a spring bolt engaging with said member for holding the same in its projected position, key controlled means for actuating said bolt, a valve chamber adapted to be connected with the gasoline supply, a valve in said chamber, levers connecting said valve with said sliding member, said sliding member having an insulated part thereon and a spring thumb contact within the casing and engaging said part when the member is in its locking position, and means for connecting said contact with the electric circuit. 110

In testimony whereof I affix my signature.

LULU M. SCOTT.
